VEHICLE ARMREST

Milton A. Berg, Winlock, Wash. 98596

Filed Nov. 3, 1967, Ser. No. 9,267

Term of patent 14 years

U.S. Cl. D15—8
Int. Cl. D12—14

FIG. 1

FIG. 3

FIG. 4

FIG. 1 is a perspective view of the vehicle armrest of my invention;

FIGS. 2 and 3 are end and front elevations of the armrest; and

FIG. 4 is a plan view of the armrest.

The seat shown in broken lines in FIG. 1 is included only for illustrative purposes.

I claim:

The ornamental design for a vehicle armrest, as shown and described.
